UNITED STATES PATENT OFFICE.

GREEN B. McDONALD, OF LOUISVILLE, KENTUCKY.

IMPROVEMENT IN RAILROAD-CHAIRS.

Specification forming part of Letters Patent No. 42,098, dated March 29, 1864.

To all whom it may concern:

Be it known that I, GREEN B. McDONALD, of Louisville, in the county of Jefferson and State of Kentucky, have invented a new and Improved Chair for Railroad-Rails; and I do hereby declare that the following is a full, clear, and exact description of the same, reference being had to the accompanying drawings, making a part of this specification, in which—

Figure 1 is a transverse vertical section of my invention, taken in the line α α , Fig. 2; Fig. 2, a plan or top view of the same.

Similar letters of reference indicate corresponding parts in the two figures.

This invention consists in constructing the chair with a base-plate, a bottom flange, and a lip, and using in connection therewith two or more hooks, all arranged as hereinafter set forth, whereby the chair may be adapted to suit rails of any size or pattern or to connect two rails of different sizes.

To enable those skilled in the art to fully understand and construct my invention, I will proceed to describe it.

A represents the base-plate of the chair, which is of flat form, presenting a plain surface both at top and bottom, and of equal thickness throughout. From one side of this base-plate a flange, B, depends, having holes α in it to admit of the shanks b of hooks C passing through, (see Fig. 1,) and at the same side of the base-plate, at its upper edge, there

is a lip, D, so curved as to fit over one side of the edge of the base of the rails, as also shown in Fig. 1, the rails being shown in red. The lip D extends the whole length of the base plate, as shown in Fig. 2. The hooks C fit over the base of the rails at the sides opposite to those over which the lip D is fitted. The shanks b of these hooks, which pass through the holes α of the flange B, have screw-threads on them to receive nuts F, by screwing up which the hooks C are drawn snugly over the bases of the rails. The hooks C pass into notches c in the side of the base-plate. By this arrangement it will be seen that the chair is adapted to rails of different patterns and size, and that the ends of two rails differing in size may be firmly secured in it, as the adjustment of one hook is entirely independent of the adjustment of the other.

The hooks are of wrought-iron. The base-plate may be either of cast or wrought iron.

Having thus described my invention, what I claim as new, and desire to secure by Letters Patent, is—

The base-plate A, provided with the pendant flange B and the lip D, in combination with two or more hooks, C, all arranged substantially as and for the purpose set forth.

G. B. McDONALD.
